UNITED STATES PATENT OFFICE

ELMER D. BARRINGER, OF CLEVELAND, OHIO

WATER-STRIP EQUIPMENT FOR FRENCH WINDOWS

Application filed June 10, 1929. Serial No. 369,638.

This invention concerns equipment for French windows and the like and has for its primary object the provision of a casement bottom trough or channel member of special construction for preventing entry, into a house or other enclosure, of water, wind, soot, rain, snow, hail, and the like, due to inclement weather, between the casement bottom and the sash bottom.

10 The solution of this problem has been attempted numerous times in the past as by disposing a channel or trough member between the bottoms of the casement and sash, the member being provided with one or more 15 weep holes providing direct communication between the trough and the outside. The objection to this arrangement is that wind, rain, and the like, during inclement weather, goes directly into the trough and seeps between 20 the innermost bottom portions of the casement and sash, into the interior of the house. It has been attempted to obviate this objectionable feature by inserting a shield between the trough member and the casement 25 bottom and disposed in front of each weep hole to prevent the wind and rain from being driven directly into the trough while permitting outflow through the weep hole. This in itself is objectionable since it involves 30 an increase in the number of parts and is easily detached, thereby rendering the trough member subject to the above noted objections.

By my invention I solve the above problem by providing a double channeled bar having 35 substantially vertical side flanges and a web disposed between the tops and bottoms of these flanges. The outer flange bottom is provided with weep holes and the web is provided with weep holes in staggered relation to the flange weep holes. By this arrangement there is no direct flow of rain, wind, and the like from the outside through 40 the flange and web weep holes to the upper side of the web. Thus in order for objectionable matter to gain access to the upper side of the web, it must follow a circuitous route. It is understood that by the time such objectionable matter has reached the web weep holes, its energy of flow has been practically 45 spent.

My invention further contemplates the provision of means in addition to the above for further minimizing the possibility of objectionable matter reaching the upper side of the web through the flange weep hole. Of course there is no objection in water and the like reaching this upper side of the web so long as it is kept from passing therefrom up between the top of the inner flange and the bottom of the sash to thereby enter the house. 50 But with the above mentioned construction, should any water, wind, and the like, reach said side of the web, its energy of motion will have been spent to such an extent that there will be no tendency on its part to move on 55 further to enter into the house.

As a still further check on the entry of objectionable matter, I provide the outer flange with an inwardly extending lip which is adapted to interlock with a strip fastened 60 to the bottom sash of a window which is hinged to the side of the casement. However, should any wind, rain, and the like enter the upper channel of the trough member from between said lip and strip, its energy of 65 motion will have been spent and it will escape through the weep holes in the web and flange bottom.

With these and other objects and advantages, the invention comprises other novel 70 constructions, arrangements, and combinations of parts as will be subsequently specified 75 and claimed.

For a full and more complete understanding of the invention, reference may be had 80 to the following description and accompanying drawings, in which—

Figure 1 is a perspective sectional view of 85 my invention applied to a casement or sill with a French window in closed position.

Figure 2 shows an end view of the illustration of Figure 1, with the window swung into 90 open position.

Figure 3 is a plan sectional view taken along the line 3—3 in Figure 2, with the front flange 95 partially broken away.

Figure 4 is an enlarged sectional perspective view of my invention.

Throughout the various figures of the drawings and following description, like ref- 100

erence characters denote corresponding parts.

The casement 1 is that of a French window, the window sash being indicated at 2, hinged to the casement at 3. The bottom 4 of the 5 sash is spaced from the lower portion 5 of the casement. Secured to the portion 5 as by screws or the like 6, is a double channel or trough member 7. This trough member comprises outer and inner substantially vertical 10 flanges 8 and 9 separated by a web 10 intermediate the tops and bottoms of said flanges. The web 10 inclines downwardly from the inner flange to the outer flange and is provided near the outer flange with a plurality 15 of longitudinally spaced weep holes 11. The outer flange 8 has at its upper end an inwardly extending lip 12 which overhangs the weep holes 11. The web 10 is provided intermediate the flanges 8 and 9 with a downwardly 20 extending rib 13 whose bottom is substantially at the same level with the bottom of flange 8. The weep holes 11 are disposed between flange 8 and rib 13. The bottom of the flange 8 has a plurality of weep holes 14 which are disposed 25 in staggered relation to the weep holes 11. Secured to the forward bottom corner of the portion 4 of the sash, is a hook strip 15 which is adapted to interlock with the lip 12 as clearly shown in Figure 1. Disposed beneath the 30 bottoms of the flange 8 and rib 13 is a strip 16 which is tightly clamped in place by the screws 6. The flange 9 extends downwardly beyond the bottoms of rib 13 and flange 8 and is provided with a pronged or other sharp 35 edged member 17 to tightly grip the casement bar 5. The upper surface of the lip 12 is upwardly inclined from the outside as clearly indicated in Figure 4. This provides for a snug fit between lip 12 and hook 15.

40 The upper bar of the casement is provided with a hook strip 18 which interlocks with a corresponding hook strip 19 provided on the upper bar of the sash 2, and the vertical bar, to which the hinge for the French window 45 is secured, is provided with a vertical rib strip 20 which is adapted to interlock with the corresponding vertical portion of the sash 2. The rib 21 of said strip fits into groove 22 in said vertical portion of the sash.

50 Directly above the hook strip 15 and secured to the sash portion 4 is a rain drip strip 23 which, as the name implies, prevents water and the like from dripping into the channel member.

55 During inclement weather, should rain and the like be blown in through weep holes 14, it will strike rib 13 which acts as a baffle plate, thereby killing a great amount of the energy of such rain and the like. The weep holes 60 11 being staggered with respect to the weep holes 14, the objectionable matter must follow a circuitous route in order to reach the upper side of the web 10. This sinuous passage results in a further diminution of the energy of 65 the rain and the like so that by the time it

reaches the upper side of the web 10, if it ever does, its energy of motion is practically entirely spent and there is no tendency for it to pass on between the bottom of sash portion 4 and the top of flange 9 to enter the house.

70 The channel member extends entirely under the sash and will therefore catch any water that comes down through the joints of the sash whether due to faulty putting of the glass or other causes, and the water will pass 75 out through the weep holes.

The channel member, strips, and fastening means for said channel member and strips may be made of rustproof material such as zinc, bronze, or the like.

80 The trough or channel member 10 is provided with a plurality of holes 24 through which fastening screws 6 pass.

Having thus described my invention, what I claim as new and desire to secure by Letters 85 Patent of the United States, is—

1. In a protective device for French windows and the like, a trough member adapted to be disposed between the bottom of a window casement and the bottom of a window 90 sash, said trough member being provided with upper and lower channels separated by a partition, means providing communication from the troughs to the weather side of said member, and a rib extending downwardly from 95 said partition to thereby act as a baffle plate for rain and the like from the outside.

2. In weather stripping of the class described, a member adapted for attachment to a sill, said member having means adapted to 100 be embedded into the sill when the member is attached in place, whereby entry of rain, wind and the like beyond said means is prevented.

3. In weather stripping of the class described, a channel member having spaced flanges adapted to engage a sill, the weather flange and the web of the channel member having weep holes, and the other flange being imperforate and having at its base means 105 adapted to be embedded in the sill when the channel member is attached thereto, whereby entry of wind, rain, and the like beyond said means is prevented.

4. In weather stripping of the class described, a channel member adapted to be attached to a sill, and means providing a drain from the upper surface of the web to the outside through the weather flange of said member, yet preventing entry of wind, rain, and the like to said surface from said flange.

5. In weather stripping of the class described, a channel member adapted to be attached to a sill, and means providing a drain from the upper surface of the web to the outside through the weather flange of said member, yet preventing entry of wind, rain, and the like to said surface from said flange, the inner flange having means adapted to 125 interlock with the sill to prevent passage of 130 the like.

wind and the like therebetween and maintain the member in firm engagement with the sill.

6. In weather stripping of the class described, a channel member having upper and lower troughs separated by a substantially horizontal web, and a rib depending from the web and dividing the lower trough into a weather compartment and a substantially air and water tight inner compartment when attached, to prevent passage of rain and the like therebeyond.

7. In weather stripping of the class described, a channel member having upper and lower troughs separated by a substantially horizontal web, and a rib depending from the web and dividing the lower trough into a weather compartment and a substantially air and water tight inner compartment when attached, to prevent passage of rain and the like therebeyond, said web having a weep hole at its weather side, and the weather side of the lower trough having a weep hole, thereby establishing communication from the upper trough through the weather compartment, to the outside.

8. In weather stripping of the class described, a sill, a window sash, a channel member on the sill and having means adapted to be embedded therein, means for maintaining the latter in tight engagement with the sill, the outer flange of said member having an inwardly projecting lip, a hook on the sash detachably receiving said lip, and instrumentalities for conducting said rain to the outside, said member having an element for preventing access of rain and the like from the outside to the inner flange.

9. In weather stripping of the class described, a channel member providing upper and lower troughs having a common bottom, the weather side of the lower trough having spaced weep holes, and the adjacent edge of said bottom having holes in staggered relation to the first named holes, whereby to provide for drainage of water while preventing entry of rain, wind, and the like to the upper trough from said weather side.

10. In a device of the class described, a member adapted to be supported by a sill and having an inverted trough provided with compartments separated by a partition, and means for preventing water contacting the sill below one of said compartments.

11. In a device of the class described, a member adapted to be supported by a sill and having an inverted trough provided with compartments separated by a partition, means for preventing water contacting the sill below one of said compartments, and means for clamping said member to a sill, said means being located between said partition and one of the trough walls, whereby said partition serves to support the member on a sill of less width than the trough.

12. In weather stripping of the class de-

scribed, a member adapted to be supported by a sill and having an inverted trough provided with compartments separated by a partition, stripping interposed between the partition and one of the compartment walls, and the sill, and means for clamping said stripping between the trough member and the sill to prevent access of water to the surface of the sill intermediate said wall and partition.

In testimony whereof I affix my signature.
